UNITED STATES PATENT OFFICE.

PHILIP P. NUNGESSER, OF CLEVELAND, OHIO.

MACHINE FOR FILLING DRY BATTERIES.

1,170,456.

Specification of Letters Patent.

Patented Feb. 1, 1916.

Application filed August 5, 1914. Serial No. 855,815.

To all whom it may concern:

Be it known that I, PHILIP P. NUNGESSER, a citizen of the United States, residing at Cleveland, in the county of Cuyahoga and State of Ohio, have invented certain new and useful Improvements in Machines for Filling Dry Batteries, of which the following is a specification.

This invention relates to an improvement 10 in machines for filling dry batteries.

In the accompanying drawings, Figure 1 is a front elevation of the machine partly in section at its top, and Fig. 2 is a side elevation thereof. Fig. 3 is a plan view of 15 Fig. 1, omitting the parts beneath the top. Fig. 4, Sheet 2, is an enlarged vertical sectional elevation of the upper portion of the machine illustrating, particularly, the pneumatic control. Fig. 5 is an enlarged 20 sectional elevation of the valves and valve casing, corresponding in the main to Fig. 4. Fig. 6 is an end view of the pneumatic valve. Fig. 7 is a detail of the link mechanism through which the valves are reciprocated.

The machine as thus shown is designed to employ a pneumatic engine for operating the tamping mechanism, but otherwise the machine is constructed more or less after 25 the pattern shown and claimed in a patent issued to The Nungesser Electric Battery Company, February 28, 1911, No. 985,691, and which was invented by me. Thus, F represents the frame which carries the working parts and is supported in upright position by any suitable means, as a wall *w* or other fixed support. The said frame is provided with a base B on a solid foundation which is adapted to withstand the constant tamping without being impaired, and has inwardly projecting arms *a*, *a'*, *a''* at 30 intervals upon which the working parts of the machine are disposed. These parts comprise a table *b* for the sectional foldable receptacle or inclosure 2 adapted to receive the battery can or jar in which the material is tamped; a hopper *h* adapted to receive the material with which the jars are filled, and a plunger *P* which operates through the bottom of the said hopper in the said jar to tamp the material therein. The said

plunger is engaged with and operated by piston *P'* in cylinder *C*, and said piston is under pneumatic control as hereinafter described. The said rod is provided with a cushioning and lifting spring *s* for the plunger as before, and a collar *c* on said rod serves as a point of engagement for a pawl 7 rigid with lever 8, pivoted at 9 and adapted to be tilted within limits to engage and 60 disengage said pawl with said collar. Control of said lever is through the cord or wire 13 and the treadle 10 below, on which the foot of the operator rests to depress the same while a jar is being tamped and 65 during which time the pawl is thrown back out of engagement or idle. But when the treadle is relieved by the operator the counterweight 12 on said lever 8 instantly reverses the lever and throws the pawl forward beneath the said collar, arresting the descent of the said plunger. By these means 70 I am enabled to instantly suspend the tamping when desired and by the same operation the tamping rod *P* is raised clear above 75 the jar to enable the jar to be removed.

The pneumatic portion of the machine is of an auxiliary character and comprises an engine with a cylinder *C* and piston *P'* therein, and a pair of combined or unitary 80 valves *v* and *v'* which control the flow of air to and from said cylinder on opposite sides of the piston, as will now be seen. Thus, the said cylinder has two ports 15 and 16, respectively, in its side which communicate with the valve chamber *C'*, and inlet and exhaust pipes 17 and 18, respectively, open into the said chamber. The two valves *v* and *v'*, have refined adjustment upon a single tubular screw-threaded stem 20, Fig. 90 5, to get exactly the right working positions and relations in respect to the said inlet and exhaust pipes and ports respectively.

A cut-off valve *v²* in the inlet passage or 95 pipe 17 controls the pneumatic pressure to the engine, and the said valve is connected by cord or wire 22 with the treadle 10, so that said treadle serves the double function of releasing the pawl 7 and of opening the 100 said valve *v²* in the same operation. This automatically starts the tamper. A spring

23 is arranged to turn and close the said valve v^2 when pressure by the foot of the operator is removed from the treadle 10. The same act liberates the pawl 7 and enables it to resume engagement with collar c as described and intercept the descent of the plunger. It will thus be seen that the control of the tamping mechanism proceeds from a source of power wholly outside of the machine, as from a line shaft or the like, and is localized in the machine through a stub shaft 24 supported in a standard or the like on the main frame F carrying a sheave or pulley 25 with which belt connection can be made from the said drive or line shaft. Pulleys or sheaves on the line shaft will fix the speed of the said sheave 25 and may, therefore, be of a size corresponding to the speed wanted. An eccentric or crank 27 is fixed on the end of said stub shaft and connected by an adjustable rod 28 with a segmental lever 30 in the link connections which extend to the valves, v , v' . The said lever is pivoted between its ends on a pivot 31 on a bracket mechanism 32 from the middle arm a' of the main frame and behind the tamping rod P. The long arm of the said lever has a segmental slot 33 lengthwise in which the connecting rod 28 from the eccentric is adjustable to and from said pivot to give more or less throw to the said lever 30, and an adjustable rod connection 34 unites the said lever 30 with the valves v , v' . A rigid arm 34' from the valve casing serves as a guide for the said connecting rod 34, and a turnbuckle 35 or like means of adjustment in said connection 34 is provided to refine the adjustments of the valves in respect to the ports which they control. It follows as a result of the operation that the engine piston P' is reciprocated and the tamping rod P therewith is operated so as to provide as rapid and as compact tamping in the battery jar as may be desired. Of course uniformity of tamping in a given jar and uniformity between jars is a desideratum in any case, and one of the advantages of the present machine over all others known to me is the speed and uniformity with which it does its work. Valves v and v' are in the form of sleeves slidably mounted on the hollow stem 20 and are adjustably held in place by nuts 21, and the upper end of the stem is open to permit the exhaust from port 15 to pass through the stem and out of an opening at the lower end of the stem and thence to pipe 18, see Fig. 5.

A peculiarity of this machine resides in the use of an independent source of power to operate the valves v and v' . In other words the movement of the valves is not dependent upon the reciprocal movements of the piston P' and plunger P, but is controlled by the adjustable operating mechanism deriv-

ing its power from pulley 25. The advantage is that the speed of the pulley may be fixed to meet any requirement in producing batteries of different grades and kinds, and when fixed, the product will be always uniform. The adjustment of the two valves on the single stem and the other adjustments affecting the throw of the valve, permit a sensitive control of the air and variable cushioning effects for the piston. 65 70 75

What I claim is:

1. A dry battery filling machine having a vertically disposed tamper and a pneumatic engine to actuate the same, in combination with a treadle, a valve controlling the flow of pneumatic energy and a stop adapted to engage said tamper operatively connected with the said treadle. 80

2. A machine as described comprising a pneumatic engine, and a tamper actuated thereby, a power driven shaft and a valve mechanism controlling the flow of energy to said engine, and means connecting said shaft and said means adapted to reciprocate the valves, in combination with a treadle, a cut-off valve for the pneumatic energy and a stop for said tamper and flexible connections between said treadle and said stop and the said cut-off valve respectively. 85 90 95

3. A battery filling machine comprising a tamper for the battery, a pneumatic engine having a piston operatively connected with the said tamper and valves adapted to control the flow of air to said engine to reciprocate said piston and tamper, in combination with a treadle, a cut-off valve for the air and means connecting said cut-off valve and treadle. 100

4. In a dry battery filling machine, a tamper and a pneumatic engine having a piston in actuating relations therewith, valves controlling the pneumatic energy and power driven means adapted to reciprocate said valves and thereby control the said energy to the engine, in combination with a treadle and means operatively connected therewith comprising a pivoted lever and a pawl thereon adapted to engage said tamper and limit the descent thereof. 105 110 115

5. A machine as described having a tamper having a collar thereon and a pneumatic engine to actuate the tamper, in combination with a power driven shaft, valves controlling the flow of pneumatic energy to said engine and means between the said valves and the said power driven shaft 120 adapted to reciprocate the valves from the said shaft, in combination with a cut-off valve to stop the flow of energy to said engine, a pawl to engage the collar on the tamper and a treadle and means therewith to close said cut-off valve and actuate said pawl simultaneously. 125

6. In a machine for tamping dry batteries,

an engine cylinder and a reciprocable piston therein and a tamping plunger connected to said piston, and valve mechanism to control the movements of said piston having operating connection with and deriving its movement from an independent source of power, in combination with a treadle and a cut-off valve adapted to stop the flow of

energy to said engine and operatively connected to said treadle to close the said valve. 10

In testimony whereof I affix my signature in presence of two witnesses.

PHILIP P. NUNGESSION.
